SET OF PLAYING CARDS

Jeane R. Garrison, Denver, Colo.

Application March 29, 1954, Serial No. 29,734

Term of patent 7 years

(Cl. D34—13)

To all whom it may concern:

Be it known that I, Jeane R. Garrison, have invented a new, original, and ornamental Design for a Set of Playing Cards, of which the following is a specification, reference being had to the accompanying drawing, forming a part hereof.

The single figure is a face view of the 16 honor cards in a set of playing cards, showing my new design.

The portions of the honor cards not shown differ from the honor card completely shown in that the central diamond is replaced by conventional indicia and the indicia in diagonal corners of each card are identical.

The remaining cards in the deck are conventional.

The cards are of no appreciable thickness, and the backs thereof are plain or conventional.

The dominant features of my new design reside in the corner indicia thereon.

I claim:

The ornamental design for a set of playing cards, as shown and described.
